UNITED STATES PATENT OFFICE.

BAPTISTE F. SANGUINETTI, OF SAN JOSE, CALIFORNIA.

COOKER.

Application filed October 31, 1927. Serial No. 230,090.

This invention relates particularly to that type of cookers used in the cooking and sterilizing of canned goods.

It is one object of the invention to provide 5 a cooker whereby the cans may be cooled under pressure subsequent to the cooking process, thereby preventing bursting of the cans.

It is another object of the invention to 10 provide a cooker of the character indicated wherein the cans may be arranged in a closed chamber and then rotated through a given path of travel and subjected to a cooking process throughout a portion of the period 15 of said rotation and then a cooling process throughout another portion of the period of rotation.

It is another object of the invention to 20 provide a cooker of the character indicated wherein the cans may be automatically fed into the chamber without substantial shock and automatically discharged therefrom after cooling.

It is also an object to provide simple and 25 efficient means for automatically feeding a charge of cans into the chamber and discharging the same therefrom.

It is still another object of the invention to 30 provide simple and efficient means for subjecting the groups of cans to successive cooking and cooling processes in the same chamber.

It is still a further object of the invention to 35 provide a cooking and cooling chamber so constructed and arranged that the force of gravity may be used to effect the passage 40 of the cans therethrough, and endwise, and a simple and effective means provided for automatically closing and sealing the chamber at predetermined intervals.

40 In the drawing:

Figure 1 is an end elevation of the machine.

Figure 2 is an enlarged sectional view of one of the chambers on line 2—2 of Figure 1.

Figure 3 is an enlarged detail sectional 45 view of a portion of one of the chamber sealing means.

Figure 4 is an enlarged view of a portion of the shaft operating the sealing means.

Figure 5 is an enlarged elevation of the 50 pinion used for driving the machine.

Figure 6 is a side elevation of the cooker, partly in section and part broken away.

Figure 7 is a section on line 7—7 of Figure 6.

55 Figure 8 is an elevation of a portion of the cooker on the end opposite to that shown in

Figure 1 and illustrating the tripping means for releasing the cans to enter the chamber.

Referring now more particularly to the drawing, I show at 1—1 a pair of standards 60 in which is revolvably mounted as at 2 a tubular shaft 3 fitted with a head 4 near one end and engaging a nonrotating tube 5. Axially mounted in the shaft 3 to rotate therewith is a smaller tube 6, this tube also communicating with a non-rotating tube as 7 so that the parts 3 and 6 may rotate and yet receive and discharge fluids as hereinafter set forth. The other end of the shaft near its standard 1 is also fitted with a head as 8 and a center tube as 9, and this shaft and tube are connected to non-rotating tubes as 10 and 11.

Each reference character 12 indicates a tubular chamber mounted upon an annular support 13 which is in turn mounted upon the 75 shaft 3 to rotate therewith. Each chamber 12 is so positioned upon the support 13 that its axis lies in a horizontal plane when in its uppermost position during the rotation of support 13 and also when in its lowermost 80 position, but is at the same time angularly positioned relative to the vertical plane in which the axis of the support lies and therefore assumes an angular position relative to a horizontal plane when between the two extreme 85 positions mentioned. In its passage from the uppermost to the lowermost positions the chamber passes through the position of greatest angularity relative to a horizontal plane as 14, a suitable angle being selected 90 that will permit cans to slide easily therethrough.

Near each end of the chamber 12 is formed a recess as 15 and 16 having valve seats 17 and 18 formed in their outer edges. These 95 recesses are enlarged on the side of the chamber directed forwardly in the direction of travel to form chambers or housings 19 and 20 for the purpose hereinafter described, the plane of each housing lying at right angles 100 to the axis of the chamber 12.

At 21 and 22 are a pair of oppositely directed and oppositely acting gate or valve members positioned in their respective recesses 15—16 and mounted upon a shaft 23 105 lying outside of the chamber 12 and parallel therewith and passing through the housings 19—20. One end of the shaft carries a pin 24 at an angle thereto, and the other end has an arm 25 mounted thereon carrying a terminal pin 26 extending laterally therefrom. The valve 21 has a hub portion 27 fitted with

a pin 28 which engages a slot 29 in the shaft 23, the said slot being directed toward the adjacent end of the shaft and having a short portion as 30 lying at right angles to the axis 5 of the shaft. A spring 31 is inserted between the hub 27 and the side of the housing 19 adjacent the end of the shaft. The valve 22 has a hub portion 32 fitted with a pin 33 which engages a slot 34 in the shaft 23, the said slot 10 being directed toward the adjacent end of the shaft. A spring 35 is inserted between the hub 32 and the side of the housing 20 adjacent the end of the shaft. The result of this construction is that when the valves are closed 15 upon seats 17 and 18 and the shaft 23 is rotated contra-clockwise the pins 28—33 move in the slots and permit the springs to unseat the valves, the continued rotation of the shaft turning the valves back into their respective 20 housings so that the chamber 12 is clear for the passage of cans. When the shaft is again turned clockwise the pin 28 first moves along the edge 30 so that no movement is imparted to valve 21 but the pin 33 advances the valve 25 22 a little ways into the chamber so as to form a stop for the cans admitted to the chamber 12. Further rotation of the shaft carries both of the valves into the chamber to center over their respective seats whereupon the slots 30 function to force them into engagement with the said seats, the positions of the pins in the slots in this last position being indicated at 36 and 37 respectively.

The cooking is effected by means of steam admitted through tube 9. Communicating with this tube is a conduit 38 communicating with an annular tube or conduit 39 lying in substantially the plane of the adjacent end of the machine. From this annular conduit 10 the steam is led to chamber 12 by means of a short tube 40 fitted with a valve 41 the stem of which is fitted with a cross handle 42. The steam enters one end of the chamber at 43 and is discharged at 44 through a conduit 45 parallel 15 the chamber 12 to a point adjacent conduit 39 where it is fitted with a valve 46 and discharges into an annular conduit 47. The annular conduit 47 communicates with the hollow shaft 2 by means of a conduit 48. When the valves 41—46 are open and the chamber 12 is closed a continuous flow of steam passes therethrough, but the valves may be closed to permit the use of a cooling fluid. Stop pins 49 and 50 mounted on standard 1 are positioned to engage the cross handle 42 of valve 41 and at the same time the handle 51 of valve 46 to open the same, and other stops are positioned as at 52—53 to close the same. These stops are indicated in dotted 55 lines in Figure 1 clearly showing their positions relative to the other operating parts hereinafter described.

The cooling under pressure is effected by means of water admitted into chamber 12 and discharged therefrom in a manner similar to 60

that just described. The water enters through tube 6 and a conduit 54 to an annular conduit 55 from which it is conducted to each chamber by a conduit 56 fitted with a valve 57 having a handle 58. Entering the chamber at 59 it 70 is discharged at 60 through conduit 61 fitted with a valve 62 having a handle 63 and into an annular conduit 64. A conduit 65 connects the annular conduit 64 with the discharge tube or shaft 2. Stops 66 and 67 are mounted on standard 1 to engage handles 58—63 to open the valves and permit water to flow through the chamber, and stops 68—69 are provided as shown to engage the handles and close the valves. By means of this arrangement the stops 49—50 first become effective to open the steam line for cooking, and subsequently stops 52—53 become operative to close the steam line, followed immediately by the stops 66—67 becoming effective to open 80 the water line for cooling and stops 68—69 for subsequently closing the water line to permit discharge of the treated cans and the reception of cans to be cooked. It is obvious, of course, that the several stops may be inserted at any desired points in the path of travel of the valve handles to secure the most efficient results in admitting and discharging the cooking and cooling fluids.

In order to operate the shaft 23 and secure 95 the timely opening and closing of the valves 21—22 in the chamber 12, I provide a cam surface at 70 so positioned as to engage the pin 26 on arm 25 at the time when the chamber is approaching its position of greatest 100 angularity and rotate the shaft 23 until the valves are open and the cans discharged. In order to accomplish the desired rotation of the assembled chambers I mount an annular rack 71 on one end thereof, and mount a mutilated pinion 72 in engagement with the rack to drive the same. The teeth at 73 rotate the chambers far enough to move the arm 25 to the substantially horizontal position shown in Figure 1 thereby swinging the valve 22 105 back into the housing 20 and permitting the discharge of the cans. When the teeth 74 again rotate the device a distance the pin 26 engages cam surface 75 and is carried downwardly a distance thereby partially closing 110 the valve or gate 22 as heretofore described. The rotation again stops while the chamber is being filled with cans, the further rotation carrying the pin 26 over the lower end of cam surface 75 thereby completely closing the 115 valves 21—22 in the chamber 12 and opening the next chamber for the discharge of cans therefrom.

It now remains to describe the means for introducing the cans into the chamber. For 125 this purpose I provide a tubular magazine 76 having a rocker arm 77 mounted on its underside and provided with upturned ends 78—79, a spring 8 being inserted between the outer end of the arm and the magazine as shown, 130

the upturned arms being formed to pass when desired into the interior of the magazine. To the end of the arm adjacent the chambers 12 is secured a spring member 81 extending 5 slightly beyond the end of the magazine. This spring is so positioned that when the chambers 12 are rotated and the shaft 23 is rotated as described, the pin 24 on shaft 23, normally lying in a vertical position, is rotated through the positions 82 and 83 to the position 84 so that it will engage the spring 81 and tilt the arm 77. Tilting the arm 77 withdraws its forward end from the magazine and allows the cans therein to slide down 10 into the chamber 12 while its upper end enters the magazine and prevents other cans from sliding in. As the chambers 12 are rotated further and the shaft 23 rotated to close the valves 21—22 the end pin 24 snaps off of the 15 spring 81, thereby permitting its forward end to enter the magazine and form a stop for the cans now permitted to slide into the magazine.

The operation of the machine may be 20 summed up as follows, following one chamber from the moment it has been filled and closed. First, the steam is admitted to the chamber for a period of time sufficient to effect the desired cooking and then shut off 25 in the manner described. Then water is passed through the chamber for any desired period of time and then shut off as described. The arm 23 is now actuated by the cam surface 30 thereby completely opening the chamber 12 at both ends and at the same time positioning the pin 24 ready to trip the device holding the cans in the magazine. The chamber having been at rest long enough to discharge the cans it is moved forwardly a distance and the arm 23 rotated clockwise a distance by cam 75 thereby partially closing 35 valve 22 and tripping the arm 77 to empty the magazine 76. Further rotation of the chamber 12 effects the complete closure of 40 valves 21—22 by cam 75, and one complete cycle has been completed.

It may now be seen that I have provided a 45 cooker wherein a number of cans may be treated at the same time, the capacity of the machine being determined by the length of each chamber 12 and the number of chambers arranged in circular formation as described, as well as the speed at which the machine is operated.

50 It is to be understood, of course, that while I have herein shown and described but one specific embodiment of the invention, changes in form, construction, and method of assembly and operation may be made within the 55 scope of the appended claims.

I claim:

1. In a cooker, an annular support revolvably mounted upon a horizontal axis, a plurality of tubular chambers disposed thereon to 60 rotate therewith and angularly positioned rel-

ative to an intersecting radial plane in which the axis of the support lies, means for alternately opening and closing each chamber, and means for passing a heating fluid and then a cooling fluid through each chamber while 70 closed.

2. In a cooker, an annular revoluble support, a plurality of tubular chambers disposed thereon to rotate therewith, each chamber being disposed to lie in a horizontal plane 75 in the uppermost point of its path of travel and in angular relation to a horizontal plane between the uppermost and lowermost points of its path of travel, means for alternately opening and closing said chambers, and 80 means for introducing first a cooking fluid and then a cooling fluid into each chamber when closed.

3. In a cooker, an annular revoluble support, a plurality of tubular chambers disposed thereon to rotate therewith, each chamber being angularly positioned relative to a horizontal plane at a point substantially midway between its uppermost and lowermost positions in its path of travel and lying in a 90 horizontal plane at the uppermost position in its path of travel, a valve mounted in each end of each chamber, and means actuated by the rotation of the chamber for swinging the valves out of the chamber and then back 95 into the chamber.

4. In a cooker, an annular revoluble support, a plurality of tubular chambers disposed thereon to rotate therewith, each chamber being angularly positioned relative to a 100 horizontal plane at a point substantially midway between its uppermost and lowermost positions in its path of travel and lying in a horizontal plane at the uppermost position in its path of travel, a valve mounted in 105 each end of the chamber, means for unseating the valves, means actuated by the rotation of the chamber for swinging the valves out of the chamber, and then back into the chamber, and means for again seating the valves. 110

5. In a cooker, an annular revoluble support, a plurality of tubular chambers disposed thereon to rotate therewith, each chamber being angularly positioned relative to a horizontal plane at a point substantially midway between its uppermost and lowermost positions in its path of travel, a valve mounted to seat in each end of each chamber, means for unseating each valve, means for swinging both valves out of the chamber, means for swinging both valves back into the chamber one in advance of the other, and means for again seating both of said valves to close the chamber. 115

6. In a cooker, an annular revoluble support, a plurality of tubular chambers disposed thereon to rotate therewith, each chamber being angularly positioned relative to a horizontal plane at a point intermediate its uppermost and lowermost positions in its 120 130

path of travel, a can magazine mounted to discharge cans into said chamber in said last mentioned position, a valve mounted to seat in each end of said chamber, means for unseating each valve, means for swinging said valves out of said chamber to permit cans to discharge therefrom, means for advancing one of said valves into the chamber in advance of the other valve, and discharging the magazine into said chamber, and then advancing both of said valves into the chamber, and means for again seating the valves.

7. In a cooker, a support revolvably mounted on a horizontal axis, a tubular chamber adapted to receive a plurality of cans mounted on the support in angular relation to its axis, oppositely directed valve seats formed in the ends thereof, a valve mounted to engage each seat to close the chamber, means for introducing a fluid into said chamber when the valves are closed, and means for swinging the valves out of the tubular chamber to permit the passage of cans therethrough.

25 8. In a cooker, a support revolvably mounted on a horizontal axis, a tubular chamber adapted to receive a plurality of cans mounted on the support in angular relation to its axis, a valve seat formed in each end of said chamber, a valve mounted to swing into and out of said chamber and into and out of engagement with each valve seat, a housing communicating with the chamber to receive each valve, and means for actuating the valves.

9. In a cooker, a tubular chamber adapted to receive a plurality of cans and means for mounting the same in an angular position

relative to a horizontal plane, a valve seat formed in each end of said chamber, a housing formed on each end of the chamber and communicating therewith adjacent said valve seats, a valve mounted in each end of the chamber and axially movable to seat on said valve seats and mounted to swing out of said chamber into said housings, and actuating means for the valves whereby to simultaneously seat and unseat the same.

10. In a device of the character described, a plurality of tubular chambers supported to move in a circular path, each chamber assuming a horizontal position at the uppermost point of its path of travel and an angular position relative to a horizontal plane when below said uppermost point, and means for introducing cans into said chambers at a given point in their path of travel.

11. In a device of the character described, a tubular chamber supported to move in a circular path and angularly positioned relative to an intersecting radial plane in which the axis of the circular path lies, means for introducing cans into the chamber at a given point in its path of travel and intermediate the uppermost and lowermost points in its path of travel, and means for discharging the cans therefrom.

12. In a cooker, a tubular chamber supported to move in a circular path and angularly positioned relative to an intersecting radial plane in which the axis of the circular path lies, means for introducing cans into the chamber at a given point in its path of travel and means for discharging the cans therefrom.

BAPTISTE F. SANGUINETTI.
